US0D1108474S

(12) **United States Design Patent** (10) **Patent No.:** **US D1,108,474 S**
(45) **Date of Patent:** **** Jan. 6, 2026**

(54) **DISPLAY SCREEN WITH GRAPHICAL USER INTERFACE**

(71) Applicant: **Wondermove Corp.**, Seoul (KR)

(72) Inventors: **Tae Won Kim**, Seoul (KR); **Hyunsuk Kim**, Seoul (KR); **Jooho Kim**, Seoul (KR); **Handeul Seong**, Seoul (KR)

(73) Assignee: **WONDERMOVE CORP.**, Seoul (KR)

(**) Term: **15 Years**

(21) Appl. No.: **29/992,990**

(22) Filed: **Mar. 12, 2025**

Related U.S. Application Data

(62) Division of application No. 35/519,312, filed on Jul. 31, 2023 (U.S. filing date under 35 U.S.C. 384), and having an international filing date of Jul. 31, 2023, now Pat. No. Des. 1,070,894.

(57) **CLAIM**

The ornamental design for a display screen with graphical user interface, as shown and described.

DESCRIPTION

The file of this patent contains at least one drawing executed in color. Copies of this patent with color drawing(s)/photograph(s) will be provided by the Office upon request and payment of the necessary fee.

The single FIGURE is a front view of a display screen with graphical user interface showing our new design.

The outermost broken lines illustrate a display screen and form no part of the claimed design.

1 Claim, 1 Drawing Sheet
